BADGE

Richard C. Murray, Kansas City, Mo., assignor to
Sertoma International, Kansas City, Mo., a
corporation of Kansas

Application September 18, 1950, Serial No. 12,241

Term of patent 14 years

(Cl. D29—2)

To all whom it may concern:

Be it known that I, Richard C. Murray, a citizen of the United States, residing at Kansas City, in the county of Jackson and State of Missouri, have invented a new, original, and ornamental Design for a Badge, of which the following is a specification, reference being had to the accompanying drawing forming a part thereof, wherein:

Figure 1 is a front elevational view of a badge, showing my new design.

Fig. 2 is a side edge elevational view thereof; and

Fig. 3 is a top edge elevational view thereof.

The dominant features of the design reside in the portions shown in full lines.

I claim:

The ornamental design for a badge, as shown and described.

RICHARD C. MURRAY.
